**NECK FOR A STRINGED MUSICAL INSTRUMENT
OR SIMILAR ARTICLE**

James Ormston Burns, Buckhurst Hill, Essex, England,
assignor to Ormston Burns Limited, Hackney, London,
England

Filed Feb. 20, 1962, Ser. No. 68,996

Claims priority, application Great Britain Aug. 24, 1961

Term of patent 14 years

(Cl. D56—1)

—FIG. 1.—

—FIG. 2.— —FIG. 3.

FIG. 1 is a front perspective view of a neck for a stringed musical instrument or similar article embodying my new design;

FIG. 2 is a left side elevational view; and

FIG. 3 is a rear elevational view thereof.

The characteristic feature of my design resides in the spindle cover shown particularly in FIGS. 1 and 2.

I claim:

The ornamental design for a neck for a stringed musical instrument or similar article, substantially as shown and described.
